SPECIFICATION forming part of Design No. 31,484, dated August 29, 1899.

Application filed July 18, 1899. Serial No. 724,312. Term of patent 7 years.

To all whom it may concern:

Be it known that I, MAGGIE B. SHOWEN, a citizen of the United States, residing at Ma-
5 con, in the county of Macon and State of Mis-
souri, have invented and produced a new and
original Design for Lap-Robes, of which the
following is a specification, reference being
had to the accompanying drawings, forming
part thereof, in which—

10 Figure 1 is an elevation of one side of the
lap-robe, and Fig. 2 is an elevation of the op-
posite side.

The leading or material feature of my de-
sign consists of the lap-robe with the widened
15 portions flaring outwardly toward the lower
end of the illustration in Figs. 1 and 2.

The lap-robe is shown as comprising the
portion A and the portion B at the lower end
of the portion A and provided with the lateral
portion C, flaring outwardly toward the lower 20
end of the robe when in the position shown
in Figs. 1 and 2. The edge of the portion B
is curved at B'.

Having described my invention, what I
claim as new, and desire to secure by Letters 25
Patent, is—

The design for a lap-robe as herein shown
and described.

MAGGIE B. SHOWEN.
